UNITED STATES PATENT OFFICE.

KENNETH S. JOHNSON, OF JERSEY CITY, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed December 22, 1920. Serial No. 432,522.

To all whom it may concern:

Be it known that I, KENNETH S. JOHNSON, a citizen of the United States, residing at Jersey City, in the county of Hudson, State 5 of New Jersey, have invented certain new and useful Improvements in Telephone Systems, of which the following is a full, clear, concise, and exact description.

This invention relates to telephone systems and in particular to a circuit arrangement and organization of apparatus employed in a telephone substation.

The object of this invention is to provide a telephone system in which interference 15 between the transmitter and the receiver associated at the same station is reduced to a minimum.

The object of this invention is attained by providing in a telephone substation a neutral receiver (one having a soft iron core which is only magnetized while current is being supplied to the receiver) and a source of energy connected in series across line conductors, the receiver being furnished 25 with energizing current only when another bridge such as an answering substation is operatively connected across the same conductors.

By properly proportioning the balancing 30 network in an anti-side-tone circuit such as provided in K. S. Johnson Patent No. 1,396,760 of November 15, 1921, with particular reference to Fig. 1, it is possible to eliminate side-tone during a conversation.

In some circuits, however, an unbalanced 35 condition exists at the calling station until the called party removes his receiver from the switch hook. This unbalance is such as to cause excessive side-tone and at times 40 howling in the receiver especially when the receiver is of the permanent magnet type and mounted in close relation or mechanically coupled with the transmitter as it is in the case of hand sets and loud speaking 45 telephone sets. By employing a neutral receiver the efficiency of which is practically zero until the called party answers and current flows through the receiver winding, 50 objectionable side-tone does not result.

Referring to the accompanying drawing, 55 Fig. 1 represents a telephone circuit embodying this invention. Fig. 2 shows a modification of this circuit. Fig. 3 shows diagrammatically a preferred relation of the transformer or electrical coil windings em-

ployed. Such a coil forms the subject matter of K. S. Johnson Patent No. 1,426,726, granted August 1, 1922.

Referring in particular to Fig. 1, line conductors 1 and 2 are connected to the terminals 3 and 4 of the substation A. Also across line conductors 1 and 2 are other substations such as B and C. Between the terminals 3 and 4 connected in series are receiver battery 5, secondary winding 6, 60 primary winding 7, transmitter battery 8, and receiver 9. Connected around primary winding 7 and battery 8 is transmitter 10 controlled by contact 12 and key 11. Shunting receiver 9 is conductor 16 controlled by 65 key 11 and by contact 13. In parallel with receiver 9 is winding 15 also controlled by key 11 through contact 14.

Winding 15 comprises resistance of a 70 value to balance the normal impedance of the line when transmitting and thereby to prevent side tone in the receiver. As described in Patent No. 1,396,760, referred to above, the value of this resistance is so chosen with respect to the transformer ratio 80 and the impedance of the line, that energy from the transmitter divides equally between the line and balancing resistance and substantially none of it flows through the 85 receiver. In the above patent, it was assumed that the substation circuit would be connected to lines of fairly uniform and constant impedance. In the system described herein, the lines may be so short that their impedances are materially changed 90 when the distant substation is connected or disconnected from the line. The resistance in winding 15 is given a value to balance the line when the distant substation is connected. It is seen, therefore, that before the distant 95 substation is connected a condition of unbalance is liable to exist and that during this condition the receiver 9 would be subject to side tone from the transmitter 10 if the receiver were in operative condition. In accordance with this invention, a type of receiver is used which is rendered operative only when the circuit is completed by closing the circuit at the distance substation. 100 Thus, at the same time that the receiver is energized, the line assumes its normal impedance and thereafter howling is prevented by reason of the fact that no energy from the transmitter reaches the receiver.

Key 11 is shown in its normal position 110

and in this position conversation may be carried on between such stations as B and C without disturbing station A. When, however, stations A and B, for example, are 5 conversing, key 11 is depressed and switch 17 at station B is closed. The transmitter circuit is then closed through contact 12, that of winding 15 through contact 14 and that of receiver 9 through switch 17 at station B. Under these conditions, shunt 16 being open at contact 13, current flows through receiver 9 and energizes it. When stations A and B are conversing a balanced condition exists at station A which has an anti-side-tone circuit and no interference results between transmitter 10 and receiver 9. However, when station A originates a call and the called station such as B has not yet answered, contacts 12 and 14 being closed by 10 key 11 and switch 17 being open, an unbalanced condition exists between the receiver and the transmitter favorable to side tone and howling in case a receiver of the permanent magnet type is employed, as a 15 receiver of this type has inherently a high efficiency under the condition of no direct current. In order to prevent interference or side tone during this interval, a neutral type receiver 9 is employed as it has inherently 20 practically zero efficiency when no direct current flows through its windings. Such a receiver depends upon an external source of energy to energize it and inasmuch as no direct current flows through the receiver 25 until connections are completed by another station, such as B, there can be no interference.

What is claimed is:

1. A telephone system comprising, a pair 40 of line conductors; a bridge across said line conductors including a transformer, a neutral receiver and a source of energy in series; a second bridge across said line conductors for completing a circuit through said receiver and source.
2. A telephone system comprising, a transformer having primary, secondary and tertiary windings; a pair of line conductors; a source of energy; a bridge across 50 said line conductors including said primary and secondary windings and said source of energy in series with a neutral receiver and said tertiary winding in parallel with said receiver; a second bridge across said line for completing the circuit.
3. In a telephone system, an electrical coil 60 comprising primary and secondary closely coupled windings and a tertiary winding loosely coupled to the primary and secondary windings; a pair of line conductors; a bridge across said line conductors including said primary and secondary windings, a source of energy and a neutral receiver in series, a transmitter in shunt across the primary winding and said source, said tertiary 65

winding in parallel with the receiver, and a second bridge across said conductors for completing the receiver circuit.

4. In a telephone system, an electrical coil comprising primary and secondary closely 70 coupled windings and a tertiary winding loosely coupled to the primary and secondary windings; a pair of line conductors; a bridge across said line conductors including a transmitter and a source of energy in parallel, a neutral receiver and a second source of energy in series with said source; a second bridge across said conductors for completing a circuit through the receiver. 75

5. In a telephone system, the combination 80 with line conductors of an anti-side-tone substation comprising a neutral receiver and a source of energy in series therewith bridged across said conductors, and a second bridge across said conductors for completing a circuit through said receiver, said substation comprising a transmitter, and means to prevent signal currents from said transmitter from energizing said receiver when said circuit is completed. 85

6. A telephone station comprising line terminals, a neutral receiver, a transmitter, a local source of energy in a path in parallel with the transmitter with respect to said line terminals and a series circuit for said 95 receiver and source adapted to be completed by means external to said station.

7. A telephone station comprising line terminals, a neutral receiver and a transmitter, a source of energy in a path in parallel with said transmitter with respect to said line terminals and in series with said receiver, and external means for completing the circuit through said receiver and source. 100

8. A telephone station comprising a transmitter, a receiver, a transformer having primary, secondary and tertiary windings and a source of energy; said receiver, said primary secondary windings and said source connected in series; said transmitter connected in shunt across said primary and said source; and said tertiary winding connected in parallel with the receiver. 105

9. A telephone station comprising a transmitter, a receiver, a transformer having primary secondary and tertiary windings, 115 a source of energy for said transmitter, a second source of energy for said receiver; the receiver, primary and secondary windings, said transmitter source and said receiver source connected in series; said transmitter connected in shunt across said primary and said transmitter source; and said tertiary winding connected in parallel with said receiver. 120

10. In a telephone station comprising a transmitter, a receiver, a transformer coil having closely coupled primary and secondary windings and a tertiary winding loosely coupled to said primary and secondary 130

windings, a source of energy for said receiver; said receiver, said primary and secondary windings, said transmitter source and said receiver source connected in series, 5 said transmitter connected in shunt across said primary and said transmitter source, and said tertiary winding connected in parallel with the receiver.

11. In a telephone system, the combination 10 with line conductors of a substation comprising a transmitter, a receiver, a transformer having primary, secondary and tertiary windings, and a source of energy; said receiver, said primary and secondary wind- 15 ings and said source connected in series,

said transmitter connected in shunt across said primary and said source, said tertiary winding connected in parallel with the receiver, and a bridge across said conductors completing a circuit through said receiver. 20

12. In a telephone system, the combination 25 with line conductors of a substation comprising, a transmitter, a neutral receiver for preventing side-tone when said conductors are open and means for preventing side-tone when said conductors are closed.

In witness whereof, I hereunto subscribe my name this 17th day of December A. D., 1920.

KENNETH S. JOHNSON.
